UNITED STATES PATENT OFFICE

FRANK H. ELLIS, OF BRAINTREE, MASSACHUSETTS, ASSIGNOR TO UNITED SHOE MACHINERY CORPORATION, OF PATERSON, NEW JERSEY, A CORPORATION OF NEW JERSEY

CUTTING BLOCK

Application filed August 20, 1929. Serial No. 387,188.

This invention relates to cutting blocks such as are used for cutting out blanks from sheet material, such as leather, by means of dies.

5 Cutting blocks of the type referred to are commonly built up of small rectangular wooden blocks glued together to form a unitary structure. Such cutting blocks are frequently subjected to great stresses during cutting operations and consequently it has been the practice to provide the blocks with reinforcing devices commonly in the form of clamping irons to strengthen the blocks better to enable them to withstand such stresses, 10 as well as to prevent distortion due to expansion and contraction caused by temperature changes and moisture.

An object of the invention is to provide an improved reinforced cutting block which, 20 without sacrificing any of the advantages of such blocks as heretofore constructed, will be still adapted to withstand the rough usage referred to as well as the effects of temperature changes and moisture. With this object 25 in view and as illustrated, the invention provides a cutting block having reinforcing members extending through the block substantially at right angles to each other, one of the reinforcing members extending 30 through the other. Preferably and as shown, one of the reinforcing members is in the form of a narrow metal plate the ends of which are illustrated as secured to clamping irons extending along the sides of the block. The 35 other reinforcing member preferably consists of a rod which, as illustrated, is held in place by plates at the ends of the block. This arrangement provides internal reinforcement both transversely and longitudinally of the 40 block but, since one of the members passes through the other, the distance taken up by the members heightwise of the block is not greater than that of clamping irons heretofore commonly used for cutting blocks. Consequently, the construction is economical in 45 that the block can be utilized for cutting purposes until its thickness has been reduced substantially to the height of the clamping irons. The construction set forth results in a 50 very rigid block the parts of which are held

tightly in position against forces which would tend to bulge the block laterally or endwise, particularly at the central portions of the sides and ends of the block. Blocks constructed in this manner are capable of 55 withstanding the pressures exerted by presser members of machines while operating upon heavy material such as thick sole leather or many plies of canvas. The reinforcing members serve to prevent the breaking down of 60 the block due to expansion caused particularly by the forcing of the edges of dies between the fibers of the block during cutting operations.

Other objects and features of the invention will be described in the following specification and will be set forth in the claims. 65

In the drawings,

Fig. 1 is a perspective view of a portion of a clicking machine with a cutting block positioned thereon, portions of the block being broken away to show the construction of the reinforcing members; 70

Fig. 2 illustrates a transverse cross-section through the cutting block; and 75

Fig. 3 is a side view of a portion of the cutting block.

For purposes of illustration the invention is disclosed as embodied in a clicking machine which comprises a bed 10, and a post 12 carrying a presser member 13 which is movable laterally over the bed and is arranged for movement toward and away from the bed in pressure-applying operations. Supported upon the bed 10 is a cutting block 14 which is 80 composed of a plurality of transverse sections or plates 16. Each of the sections 16 comprises several wooden blocks 18 which are glued together, the sections 16 being also glued together to form a unitary construction comprising the block 14. 85

The block is strengthened by means of clamping devices comprising end irons or plates 20 which are connected by bars 22. The ends of the bars 22 are reduced to form 90 screw-threaded portions 23 which extend through holes in the end irons 20, the bars 22 being placed under tension by nuts 26 on the ends of the bars. Each of the bars 22 is provided with a slot 27 extending substan- 95

5 tially the entire length of the bar. These slots are adapted to receive the ends of bolts, such as bolts 28, located in bosses 30 on the bed 10. Similar bolts 32 at the end of the bed engage the walls of holes 34 in the end irons 20. The bolts 28 and 32 constitute holding devices which secure the block to the bed.

10 The novel means for reinforcing the block will now be described. This means comprises a narrow metal plate 36, rectangular in cross-section, positioned in a groove 38 at the joint between two of the block sections 16. The plate 36 is provided with reduced screw-15 threaded ends 40 which extend through the slots 27 of the bars 22, the plate being placed under tension by nuts 42 which can be adjusted to force the bars 22 against the sides of the block. Extending longitudinally 20 through the block, the plate 36 and the end irons 20 is a reinforcing rod 44 held in position by nuts 46. The rod 44 passes through an elongated opening 48 in the plate 36 which permits lateral adjustment of the plate relatively to the rod.

25 The reinforcing plate 36 and the reinforcing rod 44 are both under tension and tend to draw the sides and ends of the cutting block together thus to prevent bulging of the block sections under heavy blows. It should be noted that the axes of the plate and rod are located in substantially the same plane with the result that the total thickness of these two members heightwise of the block 30 is not greater than the width of the plate which is less than that of the bar 22. Consequently, the block can be used until its thickness has been reduced approximately to the width of the bar 22, thus effecting economy 35 in material.

40 Having described the invention, what I claim as new and desire to secure by Letters Patent of the United States is:—

1. In a cutting block, metal reinforcing 45 members extending through the block substantially at right angles to each other, one of said members passing through another.

2. A cutting block comprising a plurality 50 of sections, a reinforcing plate extending through the block, and a reinforcing rod extending through the block substantially at right angles to the plate and passing therethrough.

55 3. A cutting block comprising a plurality of block sections, a reinforcing member extending transversely through the block, a second reinforcing member extending through the block and through the first-mentioned reinforcing member, and means for securing the reinforcing members in position.

60 4. A cutting block comprising a plurality of wooden block sections, a reinforcing plate extending transversely of the block along the 65 joint between two of the sections, and a rein-

forcing rod extending longitudinally of the block and passing through the plate.

5. A cutting block comprising a plurality of wooden block sections, a reinforcing member extending through the block in a transverse direction, a second reinforcing member extending through the block in a longitudinal direction and passing through the first-mentioned reinforcing member, and means for placing one of said reinforcing members 75 under tension.

6. A cutting block comprising a plurality of wooden sections, clamping members extending along the ends and sides of the block, and reinforcing members extending through 80 the block substantially at right angles to each other in the same plane and connected to the clamping members for counteracting the tendency of the block to bulge at the central portions of the sides and ends thereof.

85 7. A cutting block comprising a plurality of wooden sections, end plates, tension members extending along the sides of the block and connecting the end plates, a reinforcing plate extending transversely through the block and having its ends secured to the tension members, and a reinforcing rod extending through the block and reinforcing plate and having its ends secured to the end plates.

8. A cutting block comprising a plurality 95 of wooden block sections, end plates, bars extending along the sides of the block co-operable with the end plates for clamping together the block sections, the bars being provided with slots extending longitudinally 100 thereof, a reinforcing member comprising a plate having reduced end portions which extend into the slots in the bars and having an elongated opening, and a second reinforcing member connecting the end plates and extending through the opening in the plate.

105 In testimony whereof I have signed my name to this specification.

FRANK H. ELLIS.
